UNITED STATES PATENT OFFICE.

THOMAS B. JACKSON, OF BELMONT, OHIO.

HOT-AIR HEATER.

SPECIFICATION forming part of Letters Patent No. 744,760, dated November 24, 1903.

Application filed October 16, 1901. Serial No. 78,859. (No model.)

To all whom it may concern:

Be it known that I, THOMAS B. JACKSON, a citizen of the United States, residing at Belmont, in the county of Belmont and State of Ohio, have invented certain new and useful Improvements in Hot-Air Heaters; and I do hereby declare the following to be a full, clear, and exact description of the invention, such as will enable others skilled in the art to which it appertains to make and use the same.

My invention relates to heating-stoves; and it consists, essentially, of the novel construction and arrangement of the various parts, as will be hereinafter fully described, and particularly stated in the claims.

The principal object of the invention is to heat cold air taken in at any suitable point, preferably at the base, and discharge the same into the compartment in which the stove is situated or into other compartments desired to be heated. This and other objects of the invention are attained by means of the device illustrated in the drawings, in which—

Figure 1 is a front elevation; Fig. 2, a side elevation; Fig. 3, a vertical section on line 3 3 of Fig. 4; Fig. 4, a horizontal section on line 4 4 of Fig. 2; Fig. 5, a detail section of the upper part of the stove-body and fuel-magazine; Fig. 6, a perspective view of the fuel-magazine door, and Fig. 7 a detail showing the connection between the hot-air tubes or pipes of the upper and lower parts of the body.

In the several views, the letter *a* indicates the base of the stove, preferably cast in one piece, supported upon suitable legs *a'*. The base is provided with the usual ash-pit and draft-damper, as shown, and has each of its side walls provided with a series of vertical air-ducts *a²*, (only two being shown,) through which cold air is taken from the outside.

The body of the stove is preferably composed of two sections *b* and *b'*, the lower section being provided with a suitable grate *b²* and a door *b³*, opening into the fire-pot. Each body-section has its side walls provided with a series of oppositely-disposed air-tubes *b⁴*, fitted together, as shown in Fig. 7, and the upper section has a fuel-door *b⁵* and a smoke-out *b⁶*. The upper end of the upper section immediately over the combustion-chamber is closed, and a cap *c*, provided with a register

c', is fitted thereon. The cap *c* is sufficiently large to form an air-chamber *c²*, into which flows the heated air from the tubes *b⁴*, and is 55 provided with an opening *c³*, through which the heated air may be conducted to warm other compartments. The air-tubes *b⁴* are connected with the air-ducts *a²* by means of short air-tubes *b⁷*, thus forming a series of 65 continuous air-tubes from the lower part of the stove-base to the chamber *c²* in each side of the stove-body. The air-tubes *a²* are preferably inclosed by an air-chamber *d*, formed by a flaring-mouth cap *d'*, into which chamber cold air is conducted through a suitable pipe *d²*.

Supported in the upper part of the combustion-chamber formed by the body-sections is a bell-shaped fuel-magazine *e*. This fuel-magazine is provided with a hinged door *e'*, having sides *e²*, which door when dropped or pulled down is adapted to engage the bottom of the fuel-door opening and form a chute, down which the fuel may be fed into said 75 fuel-magazine.

The letter *f* indicates a water-heater, which is detachably supported in the fire-box by means of the inlet and outlet pipes *f'* and *f²*, which pass through the wall of the lower 80 body-section and are screwed into the water-heater. The pipes *f'* and *f²* may be of a length sufficient to project a short distance beyond the outer side of the heater and have their outer ends screw-threaded to receive 85 screw-threaded elbows, to which the feed and service pipes may be attached. By this construction it will be readily seen that the water-heater is suitably supported and rendered easily detachable. The water-heater is provided with a suitable draw-off cock *f³* for the purpose of cleaning said heater.

The operation of my improved heater will be readily understood from the foregoing description, it only being necessary to state that 95 when it is not desired to convey the heated air to another compartment any suitable cap or cover may be fitted over the opening *c³*, and the heated air may then be discharged into the compartment in which the heater is 100 placed. In heating another compartment the flow of heated air may be regulated by any suitable damper placed in the conducting-pipe *g*.

- It will be seen that my improved heater is of simple construction and may be readily taken apart for cleaning purposes or repair. The water-heater may be taken out when desired and the stove or heater used simply as a hot-air heater; but when the two, heating both air and water, are combined my stove or heater offers advantages not usually found in this class of stoves.
- Having thus fully described my invention, what I claim, and desire to secure by Letters Patent of the United States, is—
1. In a heating-stove, the combination with a suitable base having cold-air ducts, of two body-sections having a series of oppositely-disposed hot-air tubes formed within their walls, a series of independent tubes connecting each series of hot-air tubes with the cold-air ducts, and a hot-air chamber situated above the upper body-section and communicating with the hot-air tubes.
  2. In a heating-stove, the combination with the base thereof, having cold-air ducts, of two body-sections having a series of hot-air tubes formed within their walls, at opposite sides, the upper section provided with a fuel-door, a fuel-magazine, supported within said body-sections, having a fuel-door adapted to rest upon the lower edge of the fuel-door opening in the upper body-section, and form a chute to convey the fuel to the magazine, air-tubes

connecting the hot-air tubes and the cold-air ducts, and a hot-air chamber above the upper body-section to receive the flow of hot air from said hot-air tubes.

35

3. In a heating-stove, the combination with a suitable base provided with cold-air ducts, of two body-sections having a series of hot-air tubes formed within their side walls, each series connected with the cold-air ducts by a series of independent tubes, a hot-air chamber, above the upper body-section, with which the hot-air tubes communicate, and a detachably-connected water-heater situated within the fire-pot.

45

4. In a heating-stove, the combination with the two body-sections having a series of oppositely-disposed hot-air tubes formed within their walls, a hot-air chamber situated above the upper body-section and communicating with the hot-air tubes, of a suitable base provided with a series of cold-air ducts, a series of independent tubes connecting each series of hot-air tubes with the cold-air ducts, and a cold-air chamber inclosing said cold-air ducts, said chamber having an air-inlet.

50

In testimony whereof I affix my signature in the presence of two witnesses.

THOMAS B. JACKSON.
